COMBINED BACK SCRATCHER AND SHOE HORN

Henry Wedermeyer, 1140 Broadway,
New York, N.Y. 10001

Filed Mar. 1, 1967, Ser. No. 6,019

Term of patent 14 years

(Cl. D86—10)

I claim:

The ornamental design for a combined back scratcher and shoe horn, as shown.
